US0D1106508S

(12) **United States Design Patent** (10) **Patent No.:** **US D1,106,508 S**
(45) **Date of Patent:** **** Dec. 16, 2025**

(54) **CONSTRUCTION ELEMENT**

- (71) Applicant: **SPACECUBE IP PTY LTD**,
Dandenong South (AU)
- (72) Inventors: **Jeremy Nicholas Fisher**, Kalapoi (NZ);
Anton Shilo, Caulfield (AU)
- (73) Assignee: **SPACECUBE IP PTY LTD**,
Dandenong South (AU)

(**) Term: **15 Years**

(21) Appl. No.: **29/862,905**

(22) Filed: **Dec. 13, 2022**

(30) **Foreign Application Priority Data**

Jun. 14, 2022 (AU) 202213413
Jun. 14, 2022 (AU) 202213414

(57) **CLAIM**

The ornamental design for the construction element, as shown and described.

DESCRIPTION

FIG. 1 is a top, rear, left side isometric view of a construction element showing our new design according to one embodiment;

FIG. 2 is a bottom, front, right side isometric view of the construction element of FIG. 1;

FIG. 3 is a front elevation view of the construction element of FIG. 1;

FIG. 4 is a rear elevation view of the construction element of FIG. 1;

FIG. 5 is a left side elevation view of the construction element of FIG. 1;

FIG. 6 is a right side elevation view of the construction element of FIG. 1;

FIG. 7 is a top plan view of the construction element of FIG. 1; and,

FIG. 8 is a bottom plan view of the construction element of FIG. 1.

The shade lines in the Figures show surface contour and not surface ornamentation.
